UNITED STATES PATENT OFFICE.

PAUL W. MERKLE, OF LONDON, ENGLAND.

MOUNTING FOR RING-KNIVES FOR PARING OR SPLITTING LEATHER.

1,167,422.

Specification of Letters Patent. Patented Jan. 11, 1916.

Application filed December 30, 1913. Serial No. 809,463.

To all whom it may concern:

Be it known that I, PAUL W. MERKLE, a citizen of the German Empire, residing at London, England, have invented a new and useful Improvement in Mountings for Ring-Knives for Paring or Splitting Leather, of which the following is a full and accurate specification.

In machines for paring and splitting leather, the so-called ring knives are used almost universally, in place of the old plane disk knives, that is, knives with a retracted foundation and a projecting ring-formed cutting part. These knives have the advantage that it is possible to often sharpen and use them, without changing the diameter, the speed of cutting, or the position of the knife-carrying shaft. However, such a knife is a sensitive part of the machine. It must be perfectly seated upon the knife-carrying shaft and revolve perfectly, and be easily replaced at the same time.

The perfect fitting and revolution of the knife, together with ease of replacing, have already been attained, as the cutting part of the knife and the strong walled foundation part have been made of one piece, and this one-piece knife has been adjusted to a flange of the knife-carrying shaft by means of a central boring, and then been fastened with several screws. This means of fastening fulfilled the requirement, it is true, with respect to an accurate and secure fastening, but still had a defect, due to the nature of its operation. The screws had to be unfastened by means of a screw-key, for replacing the knife. In the manipulation with the screw-key the edge of the knife was easily injured or the hands of the operator were cut. The changing of the knife was, therefore, a delicate and dangerous operation.

The present invention is designed to overcome this difficulty, and to provide for a rapid and safe means of mounting and dismounting the knife, without any injury to the sharp edge.

It consists essentially of means for pressing the knife against the flange of the knife-carrying shaft, which means are removed or brought into action by means at the end of the driving shaft opposite to the end carrying the knife.

The following drawings and description show one embodiment of my invention.

55 The drawing shows a section through the diameter of the knife-carrying shaft.

The ring-knife *a* has a cylindrical boring *b* in its thick-walled foundation, which is concentric with respect to the cutting edge of the knife, and is keyed thereby to the 60 cylindrical central flange *c* of the hollow knife-carrying shaft *d*. The shaft *d* is placed in a suitable journal *f* in the frame of the machine, as for example, between the table plates *g*. It is preferable to not join 65 the driving pulley *h* (and other pulleys *i* for actuating special parts of the machine) directly to the knife-carrying shaft *d*, but to a special driving shaft *k*, which is non-rigidly connected to the knife-carrying 70 shaft *d*, and drives it by means of the pin coupling *l*.

A plate *q* serves to grip the knife to the flange *e* of the shaft *d*, which has a pin-like projection *r*, which naturally need not be 75 made in one piece with the plate *q*, which projection *r* fits into a corresponding boring or a radial slit of the knife foundation and the flange *e*. The plate *q* has an internal threading into which the screw bolt *m* in 80 the hollow knife-carrying shaft *d* can be secured. The bolt *m* is fastened with a hoop or the like against that end of the shaft *d* that is away from the knife, and is extended and led out to an easily accessible position 85 in the machine to end in a head *p*, as for example, by an extension *n* secured thereto, and jointed or linked at *o*. In the embodiment illustrated, the part *n* of the bolt *m* lies in the hollow driving shaft *k*. 90

To secure the knife to the shaft *d*, the knife is thrust together with the plate *q* on to the cylindrical head *c* of the flange *e*, so that the pin *r* of the plate *q* prevents the plate *q* and the knife from revolving. Then 95 the knife is mounted by simply tightening the bolt *m* by means of the head *p*, so that the threadings of the bolt *m* are screwed into the plate *q*. If desired, the part *n* of the bolt *m* could be keyed thereto at the 100 coupling *o*, so that, after the plate *q* had been gripped by means of the bolt *m*, the part *n* could be removed from the machine, and keyed again to loosen the plate *q*, but this would somewhat lessen the ease of 105 manipulation of the mounting.

Having described my invention, what I desire to secure by Letters Patent is:—

1. In machines for paring and splitting leather, the combination of a ring knife, 110 and means for fastening said knife to its shaft, comprising a fastening member and

- controlling means capable of attachment to said fastening member, said controlling means being capable of manipulation outside of the hollow of said ring knife.
5. 2. In a machine for paring and splitting leather, the combination of a ring knife, and means for fastening said ring knife to a shaft, comprising a fastening member and means for controlling said fastening member, the major portion of said controlling means being located behind the hollow of the said ring knife.
3. In a machine for paring and splitting leather, the combination of a ring-knife, a hollow shaft having a flange on which said ring knife is mounted, a bolt lying in said hollow shaft and capable of manipulation behind the ring knife, and means for engaging said bolt and said ring knife to 20 fasten said ring knife to said flange.
4. In a machine for cutting and paring leather, the combination of a ring knife having a boring, a hollow shaft having a flange on which said ring knife is mounted, a plate capable of being placed on the foundation plate of said ring knife within the hollow thereof, and a bolt lying in said hollow shaft and capable of projecting through said boring of the ring knife, 25 said first-mentioned plate and said bolt being constructed for interengagement to fasten said ring knife to said flange.
5. In a machine for cutting and paring leather, the combination of a ring knife, a shaft having a flange, a plate capable of being placed on the foundation plate of said ring knife within the hollow thereof, a fastening member for fastening said plate to said ring knife, means for fastening said 30 foundation plate and said shaft at a plurality of points, whereby the ring knife is secured against revolution and radial movement on the shaft, and means for manipulating said fastening member located outside the hollow of the knife.
45. 6. In a machine for cutting and paring leather, the combination of a ring knife having a central boring, a hollow shaft for carrying said ring knife and having a flange for engaging said ring knife, a plate 50 capable of being placed on the foundation plate of the knife within the hollow thereof, said plate having a projection passing through a boring in the foundation plate and through a recess in the said flange of said shaft, a bolt lying in the hollow of said shaft and capable of passing through the central boring of the ring-knife, said first-mentioned plate and said bolt being constructed for interengagement to fasten said 60 ring knife to said shaft, and means for manipulating said bolt, behind said ring-knife.
7. In a machine for cutting and paring leather, a ring knife mounted on a hollow 65 shaft, a bolt in the hollow of said shaft, means for engaging said bolt and said ring knife for fastening said ring-knife to said shaft, and a manipulating extension on said bolt for engaging and disengaging said 70 bolt from said means, said manipulating extension projecting through that end of the shaft removed from the ring knife.
8. In a machine for cutting and paring leather, a ring knife having a back with a 75 central opening therein, a member engaging the back of the ring knife at one side thereof, a second member engaging the back of the ring knife at the other side thereof, an extension on the first member, an extension 80 on the second member, one of said extensions alongside the other, and both extending away from the knife, and means away from the knife on one of the extensions for moving one member from the other to release the knife from between the members. 85
- In testimony that I claim the foregoing as my invention, I have signed my name in presence of two subscribing witnesses.
- PAUL W. MERKLE.
- Witnesses:
- TRACY LAY,
O. J. WORTH.
